LAMP TO ILLUMINATE THE KEYBOARD AND
MUSIC RACK OF ORGANSWalter L. Caldwell and Samuel G. Bowman,
Pittsburgh, Pa.

Application January 29, 1952, Serial No. 268,806

2 Claims. (Cl. 240—4)

1

Our invention relates to the illumination of the keyboard and stops of an organ console, as well as the music supported on the usual rack of the console, and consists in an illuminating device embodying certain new and useful improvements, whereby, in accordance with the aims of the invention, efficiency in service is obtained in largest measure. It is further an aim to provide an illuminating device which may be mounted upon a music rack, without interfering with the swinging of the rack between upright position and horizontal position, the latter position permitting the console to be closed over the keyboard.

This application is a continuation-in-part of application 81,145, filed April 2, 1949, now abandoned.

The invention will be understood upon reference to the accompanying drawings, in which:

Fig. 1 is a fragmentary view in perspective of an illuminating device of the invention in service position upon an organ console;

Fig. 2 is a view comparable with Fig. 1, showing the music rack swung downward into position over the keyboard, with the illuminating device appropriately adjusted on the rack;

Fig. 3 is a fragmentary cross-sectional view, showing the rack and illuminating device to larger scale; and

Fig. 4 is a view of the illuminating device in plan, with the body of the device medially discontinued, to permit a showing on as large scale as may be.

The device of the invention consists, as the drawing shows, in an elongate body having a substantially vertical back portion 2 hinged, at 3, to a horizontal basal portion 4. The device is designed to be mounted at the lower edge of the music rack 5 of the conventional organ console C. The rack 5 is hinged at its lower edge, as at 6, to the body of the console immediately above the keyboard K.

The basal portion 4 of the device comprises a body 7—in this case formed of wood—sheathed with sheet aluminum 8, save at the top of the body where the sheath consists in a web of corrugated rubber 9. The web of corrugated rubber 9 provides an excellent support for the lower edges of the sheets or books of music positioned on the rack 5 for the player to read. The sheet 8 is secured by screws 10 to the internal body 7 of the device, while the web 9 may be secured by cement.

The body 7 is fashioned to provide within the sheath 8, 9 an elongate recess 11, in which recess a fluorescent lamp 12 is supported by and between

2

terminal brackets 13 and 14. The body 7 is channeled, as at 15, to receive electric circuit wires 25 leading to the terminal brackets 13 and 14, and at the right-hand end (Fig. 4) of the structure the body 7 is further recessed, as at 16, to receive an electric switch 17, which is secured to the adjacent end wall of the sheath, with its toggle arm 18 exposed for manipulation externally of the structure. Externally of the structure, the circuit wires, contained in a common flexible tube 35 of rubber or the like, will be understood to extend so far as may be required to make conventional connection, say by means of a plug and socket (not shown) to a source of electric power. 15 By throwing the arm 18 between "on" and "off" positions, the lamp 12 may be lit and shut-off, as desired.

Referring to Fig. 3 particularly, it will be noted that the sheath 8 above and below the lamp 12 includes slots 19 and 20, respectively. The light generated by the lamp is directed upwardly through slot 19 to illuminate the sheets of music positioned upon the base 4 and rack 5, while the light of the lamp is simultaneously directed 20 downwardly through slot 20 to illuminate the keyboard K.

A feature of the invention is found in the means for mounting the illuminating device upon the console C. More particularly, the back portion 2 of the device, to which the basal portion 4 is hinged, is constructed in the form of an elongate metal loop having a lining 21 of felt. This loop is slipped over the top edge of the rack 5, and then the device is lowered until the bottom of the 30 inner edge of the portion 4 bears upon the edge of the console above the keyboard, as indicated at B in Fig. 3. Thus, a firm attachment of the illuminating device to the rack 5 is obtained, and the basal portion of the device is rigidly sustained in rigid position overhanging the keyboard, efficiently to perform its intended functions.

When it becomes desirable to close the console, the rack 5 is swung on its hinge 6 into horizontal 45 position. In order to permit this, however, the illuminating device must be removed from the position of service in which it is shown in Figs. 1 and 3, since otherwise the body of the device would interfere with the movement of the rack 50 on its said hinge. A consideration of Fig. 3 will make clear such fact. By virtue of the structure of our present invention, no problem is encountered, since the engagement of the illuminating device with the organ console admits of the 55 movement of the device into a position where it

is out of the way, permitting the rack to be swung into horizontal position, while still maintaining the device in engagement with the rack.

It will be perceived that the engagement of the illuminating device with the organ console is a sliding engagement, found in the telescopic union of the portion 2 of the device with the rack. To permit the swing of the rack on its hinge it is merely necessary to slide the device upward upon the body of the rack and then to swing the rack downwardly into the position in which it is shown in Fig. 2. Thus, the rack overhangs the keyboard, and the illuminating device is sustained by the rack, with its basal portion 4 folded upwardly against the body of portion 2. In consequence of such adjustment of the parts the usual hood or cover of the console may be closed, as will be readily understood by those skilled in the art.

When console is reopened preparatory to playing the organ, the rack 5 is returned to upright position and illuminating device is readily slid downward upon the rack and restored to the service position in which it is shown in Figs. 1 and 3.

Several modifications of the structure described will occur to those skilled in the art, and certain variations may be made, without departing from the spirit of the invention defined in the following claims.

We claim:

1. An illuminating device for an organ having a console, a keyboard, and a music rack above the keyboard hinged to the console to swing between upright and horizontal positions, said device comprising an elongate, relatively narrow, music-supporting basal portion including an elongate electric lamp, said basal portion having slots opening severally above and below said lamp, and a vertical portion to the lower edge of which said basal portion is secured, said vertical portion

being formed as a loop telescopically engaging said music rack and arranged when said rack is upright to secure the device with its said basal portion overhanging said keyboard in position for said lamp to direct light through said slots upon music supported on the rack above and upon the keyboard below, said device being vertically adjustable in its telescopic engagement with said rack, to permit said rack to be swung on its hinge into horizontal position over the keyboard while retaining the device in engagement with the rack.

2. An illuminating device for an organ having a console, a keyboard, and a music rack above the keyboard hinged to the console to swing between upright and horizontal positions, said device comprising an elongate, relatively narrow, music-supporting basal portion including an elongate electric lamp, said basal portion having slots opening severally above and below said lamp, and a vertical portion to the lower edge of which said basal portion is hinged, said vertical portion being formed as a loop adapted telescopically to engage said music rack in upright position for securing the device with its said basal portion overhanging said keyboard in music-supporting position in which said lamp directs light through said slots upon music on the rack above and upon the keyboard below, said device being vertically adjustable in its telescopic engagement with said rack, to permit said rack to be swung on its hinge into horizontal position over the keyboard while retaining the device in engagement with the rack and the basal portion of the device swung on its hinge upwardly again said loop.
